DESIGN FOR A CASSEROLE

Thomas Kapner, Bellaire, Ohio, and David Kamenstein, New York, N. Y.

Application August 19, 1942, Serial No. 107,969

Term of patent 3½ years

To all whom it may concern:

Be it known that we, Thomas Kapner and David Kamenstein, citizens of the United States, residing in Bellaire, Belmont County, State of Ohio, and the Borough of Manhattan, city, county, and State of New York, respectively, have invented a new, original and ornamental Design for a Casserole of which the following is a specification, reference being had to the accompanying drawing, forming a part thereof, in which:

Fig. 1 is a top plan view of a casserole embodying our new design;

Fig. 2 is a side elevational view;
Fig. 3 is a bottom plan view thereof; and
Fig. 4 is a transverse vertical section taken on line 4—4 of Fig. 1.

We claim:
The ornamental design for a casserole, as shown.

THOMAS KAPNER.
DAVID KAMENSTEIN.
